UNITED STATES PATENT OFFICE.

EARL B. HOFF, OF CLEVELAND, OHIO, ASSIGNOR TO ELECTRIC VACUUM CLEANER COMPANY, INC., A CORPORATION OF NEW YORK.

WASHING-MACHINE.

1,334,097.

Specification of Letters Patent. Patented Mar. 16, 1920.

Application filed October 17, 1919. Serial No. 331,419.

To all whom it may concern:

Be it known that I, EARL B. HOFF, a citizen of the United States, residing at Cleveland, county of Cuyahoga, State of Ohio, 5 have invented certain new and useful Improvements in Washing-Machines, of which the following is a specification.

The present invention relates to washing machines and has for its object to improve 10 and simplify their construction.

For a consideration of what I believe to be novel and my invention, attention is directed to the accompanying specification and the claims appended thereto.

15 In the attached drawing which is illustrative of my invention, Figure 1 is a vertical section of a washing machine; Fig. 2 is a plan view of the bells; Figs. 3 is a diagrammatic view illustrating the path of 20 each of the bells while the machine is in operation; Fig. 4 is a detail view of the socket of the bell carrying yoke, and Fig. 5 is a sectional view of a slight modification of 25 the bearing member which supports the bell carrying yoke.

5 indicates a base or frame of any suitable construction having three or more supporting legs 6. 7 indicates the tub or casing and 8 the cover thereof, which has an internal 30 vertical flange 9 and a horizontal flange 10, the two serving to prevent water from splashing over the sides of the tub and to hold the cover in the correct position. The bottom 13 of the tub is arranged in a series 35 of steps 14 and the lowest portion is provided with a suitable drain, not shown, by means of which water can be easily removed after use. The stepped arrangement also serves to stiffen the bottom of the tub.

40 15 indicates a vertical column or pillar which is located centrally of the tub and extends through the bottom for a short distance. It is screw-threaded at its lower end into an upwardly extending boss 16 formed 45 on one of the upper frame members. The stepped arrangement of the bottom of the tub provides sufficient space for this purpose. Where the pillar passes through said bottom it is provided with a nut 17 which 50 when screwed into place clamps the bottom between it and the boss and makes a watertight joint to prevent leakage. One or more gaskets are commonly employed between the meeting surfaces to assist in making a good 55 seal. The tub is seated directly on the

framework and the arrangement of the base, pillar and nut hold the parts in their proper relation. This arrangement affords a very simple means for assembling or taking down the machine. The upper end of the pillar 60 terminates in a bearing 18. Located within the pillar and extending completely through it is a vertical shaft 19, the upper end of which is provided with a wabbler crank 20 which is inclined at a substantial angle to 65 the vertical axis of the shaft. This crank imparts the peculiar wabbler motion to the bells as will appear later.

The lower end of the shaft 19 extends into the hub 21 of a large friction wheel 22, said 70 wheel being free to turn thereon. On the lower end of the shaft is a disk 23 by means of which the wheel is supported. Mounted on the hub of the wheel is a pinion 24 which meshes with the gear wheel 25. Above this 75 wheel and mounted on the same spindle 26 is a small intermediate gear 27 which in turn meshes with the gear 28 keyed or otherwise fastened to the lower end of the vertical shaft 19. The friction wheel and the 80 above described gears form a speed reducing means between the electric motor 29 and the vertical shaft 19. The rotating element or armature of the motor has a friction wheel 30, shown in dotted lines, which engages the periphery of the large wheel 22 and drives it. The motor itself is supported on one of the vertical legs of the frame. The motor and driven parts are close up to 85 the bottom of the tub, an arrangement which prevents water from affecting them, and also 90 prevents accidents. The driven wheel is provided with an enlargement 31 which forms a housing for the gears and renders it practically impossible for any foreign 95 matter to get into them. Any lubricant applied to the gears is also confined to the region of the gears by the shape and character of the housing. In the housing is also provided an oil hole 32 to feed lubricant to 100 the supporting and bearing disk 23.

The upper end of the shaft 19 below the crank is provided with a thrust collar 33 which rests on the upper end of the pillar and in this manner supports the weight of 105 the friction wheel 22. Mounted on the inclined or wabbler crank 20 which has an orbital movement defining an inverted cone as well as a rotary movement, is a bearing member 34 upon which is seated the part 110

35, the latter having a socket 36 which fits over said member and is prevented from turning thereon by the flat faces 37, Fig. 4, or equivalent means. The parts 34 and 35 5 form a yoke for supporting and actuating the bells. They can be formed in one piece but for simplicity of construction it is preferable to make them separate. Further, since wear will in time take place, it is better to have the part in which it takes place 10 replaceable at a small expense. Also it permits of the use of different kinds of metal, which is particularly desirable where a good bearing surface is required. The yoke has arms 38, each of which terminates in a flat spring member 39 which carries a bell 40. The ends of the spring arms are turned inwardly to prevent them from catching the material which is being introduced and removed from the tub. 15 20

I have shown three angularly displaced arms and bells since this arrangement has proved satisfactory in practice and causes the proper processional movement of the material being washed in the tub. With three bells the agitation of the water is very marked and thorough washing is effected. Attached to each bell is a rod 41 which terminates at its upper end in a ball the latter 25 being contained in a cup 42 that is held in place by a screw and nut 43. In other words, each bell is connected to the yoke by a supporting spring and ball-and-socket joint which permits the bell to accommodate 30 itself to various thicknesses of material being washed and to irregularities in the surface thereof. 35

In order to effectively utilize the bells to force water through the material being washed on the downward stroke and to suck water up through it on the upward stroke, it is necessary to provide means for controlling their movements. It is also necessary in order to obtain the best results to provide 40 means for slowly rotating the material within the tub while being washed in order that all of it may be brought successively under the action of the bells. This rotation or processional movement must be slow 45 since otherwise there is a tendency for the material to be wound around the pillar. It has been proposed to slowly rotate the yoke and bells during the washing operation, *i.e.*, while the bells are working up and down 50 but this requires additional apparatus and adds of course to the expense and complexity of the apparatus as a whole. I have invented or discovered an arrangement of parts whereby a very simple means suffices 55 for both purposes. To this end a pin 44 or equivalent device is mounted on the bearing member 34 of the yoke and arranged to move up and down in a vertical slot 45 formed in a substantially spherical head 46, the latter being mounted on the upper end 60

of the pillar 15 and held against movement both angular and vertical by small screws 47. The head rather closely surrounds the member 34 of the yoke so as to prevent as fully as possible water due to splashing from having access to the shaft and crank. The head is also provided with a downwardly inclined portion which covers the thrust collar 33, and any water which gets into the head has a chance to drain out through the lower end of the slot 45. The slot 45 is made slightly longer than the total vertical travel of the pin 44 and of a width slightly greater than the diameter of the pin. 70 75

As the shaft 19 is slowly revolved the 80 crank 20 is also revolved and in addition is given an orbital movement in the path of an inverted cone. The pin 44 and walls of the slot 45 prevent the bearing member 34 of the yoke from rotating with the crank and 85 shaft. As a result of this arrangement the bells are successively depressed to the bottom of their strokes and then raised to the upper ends. The net result of the action of the various parts is to impart to the yoke 90 and bells a wobbler action, the bells moving in substantially vertical planes. Each bell has an orbital movement which is indicated diagrammatically at 48 in Fig. 3. This figure is a view looking from the axis of the 95 shaft outwardly with the friction wheel 22 moving in a counter-clockwise direction. It will be noted that the major axis of the diagram is rearwardly inclined from the vertical. As the crank moves in its orbit each 100 bell is successively depressed as indicated by the arrow 49; this downward movement being at an angle to the vertical causes the bells to push the material in the tub or casting in a counter-clockwise direction by successive steps with the result that they slowly circulate or progress and at the same time are prevented by their slow movement from winding around the pillar 15 which would of course be highly objectionable. The upward or suction movement of the bell in its 105 orbit has very little effect in moving the material being washed because the lower part of the upstroke where the bell is in the water is substantially vertical, but such effect as it 110 has appears to aid the down stroke in this particular. In brief, it may be stated that the material being washed is on each complete stroke of the bell advanced by an amount substantially equal to the short axis 115 of the orbit 48, the arrow 50 indicating the direction of movement of the material. Of course, in a construction of this kind where the bells are alternately dipping into the water, where the material being washed is 120 constantly undergoing changes in thickness, etc., and where different amounts are apt to be present, it is rather difficult to specify the exact amount of its progress around the tub but irrespective of the amount of movement 125 130

it does circulate and at such a rate as to bring different parts successively under the bells with the result of thoroughly washing the same.

5 In the operation of the machine, there should be enough water in the tub to insure each bell dipping into it before it reaches the lower end of its orbital movement. The yoke and bells can be readily removed if 10 desired, either for the purpose of inserting and withdrawing material or for cleaning and drying the parts after use. No special means are necessary to hold the yoke on the member 34 against upward thrust because when the pressure on the bell is at its maximum as for example, on the right-hand bell in Fig. 1, such thrust is taken by the inclined yoke member 34 and the crank.

By preference the friction wheel 30 is 20 made of insulating material such as rubber, and the motor 29 is well insulated from the frame so as to eliminate all danger to the operator in case the electrical apparatus should become grounded.

25 In Fig. 5 is illustrated a modification of the invention which is particularly well adapted to prevent water which is splashed about by the bells from getting into the bearings of the machine and into the central pillar. The arrangement also has the 30 advantage that the bearing member can be more readily removed when for any reason it is necessary or desirable. 16 indicates the central pillar, 19 the shaft and 20 the wabbler crank. Mounted on the upper end of the pillar and held in place by screws or other means is a head 46 which is provided with a spherical enlargement 51 having one or two vertical slots 52. As shown two such 40 slots are provided and arranged diametrically opposite. The bearing member 34 instead of being located inside of the head as in Fig. 1 is arranged to surround the upper end thereof. To this end said member is 45 provided with a downwardly extending skirt 53 which completely covers the spherical portion of the head. The under surface of the skirt is generally spherical in form and is separated from the head by a relatively small clearance to prevent the free 50 entrance of water when the machine is in operation. The opposite sides of the skirt are reinforced by vertical ribs 54 and supported by said reinforced portions are two pins 55 having enlarged heads which enter the slots 52 and prevent the bearing member from 55 rotating with the wabbler crank.

All of the motive parts are under the tub 60 and close to its bottom so as to be out of the way and free from any water which may be splashed about. This is of particular importance where an electrical motor is used and which, if wet, would be short-circuited and probably destroyed. By arranging all 65 the working parts below the cover and in-

dependent thereof, the washing operations are much simplified and the necessity of special water-tight packings or joints avoided. The member 34, Fig. 1, can be easily removed by first taking out the screws 47 in 70 the head, then the screw and washer in the outer end of the crank, and raising it and the head at the same time.

From the foregoing it will be seen that the most important feature of my invention is 75 the provision of a simple means for actuating the bells, together with an arrangement of parts whereby processional movement of the material being washed is obtained with a stationary tub and a non-rotating yoke 80 which actuates the bells.

Owing to the fact that the center of the tub is higher than the outer portion, the material being washed has a tendency to move 85 away from the central pillar and toward the outer wall. Due to this arrangement and to the action of the bells, the material being washed has a sort of cork-screw motion as it moves about. The advantage of this resides in the fact that the material being washed 90 does not maintain itself in definite layers at all times, and hence that which formed the upper layer at one time later on becomes an intermediate or bottom layer with the result that all of the material in the course of op- 95 eration of the machine is brought under the direct action of the bells.

In accordance with the provisions of the patent statutes, I have described the principle of operation of my invention, together 100 with the apparatus which I now consider to represent the best embodiment thereof, but I desire to have it understood that the apparatus shown is only illustrative and that the invention may be carried out by other means. 105

What I claim as new and desire to secure by Letters Patent of the United States, is:—

1. In a washing machine, the combination of a stationary tub adapted to receive water and the material to be washed, a vertical 110 shaft which rises from the bottom of the tub and has a wabbler crank at its upper end, bearing means for holding the shaft in its upright position, a yoke and bells mounted on the crank and in which the latter is 115 free to rotate, means which prevent the yoke and bells from rotating while permitting the crank to impart thereto a wabbler action, and means located under the tub for continuously rotating the shaft, said means 120 acting on the lower end of the shaft.

2. In a washing machine, the combination of a tub, a support rising from the bottom of the tub, a vertical shaft held in position by the support, a crank on the upper end of 125 the shaft which is inclined to the axis thereof and has an orbital movement defined by an inverted cone, a yoke carried by the crank, bells carried by the yoke, each of which has an orbital movement, the major 130

axis of which is generally vertical, means which prevent the yoke from rotating but permit the bells to be alternately depressed and raised, and means located below the bottom of the tub for rotating the said shaft.

3. In a washing machine, the combination of a tub, a support rising from the bottom of the tub, a vertical shaft held in position by the support, a crank on the upper end of the shaft which is inclined to the axis thereof and has an orbital movement defined by an inverted cone, a yoke carried by the crank, a plurality of bells carried by the yoke and angularly displaced, each of which has an orbital movement whose major axis is generally vertical, a device carried by the support, a second device oscillating with the yoke and coöperating with the first to prevent rotation of the yoke and bells, a motor located below the bottom of the tub, and speed reducing gearing also below said bottom for transmitting motion to the lower end of the vertical shaft.

4. In a washing machine, the combination of a tub, a hollow pillar rising vertically from the bottom of the tub, a shaft located within the pillar and guided thereby, a crank at the upper end of the shaft, which is inclined to the axis thereof, a yoke member mounted thereon in which the crank is free to turn while moving it in an orbit defined by an inverted cone, a pin carried by the member, a device carried by the pillar with which the pin engages to prevent rotation of the member while permitting it to describe its orbital movement, a plurality of arms carried by the yoke member which are angularly displaced, bells carried by the arms, each of which has an orbital movement, the major axis of said orbit being slightly inclined to the vertical to cause precessional movement of the material being washed, a motive power agent, and means transmitting motion from the agent to the lower end of the shaft.

5. In a washing machine, the combination of a tub, a hollow pillar rising vertically from the bottom of the tub, a shaft located within the pillar and guided thereby, a crank at the upper end of the shaft which is inclined to the axis thereof, a member mounted thereon in which the crank is free to turn while moving it in an orbit defined by an inverted cone, a pin carried by the

member, a head which is mounted on the upper end of the pillar, and has a narrow slot on one side in which the pin rides vertically to prevent rotation of the member, a plurality of arms carried by the yoke member, each terminating in a spring, bells carried by the springs, each of which has an orbital movement in a direction which is slightly inclined to a vertical plane, and means for applying power to the lower end of the shaft for rotating it.

6. In a washing machine, the combination of a hollow pillar rising vertically from the bottom of the tub, a shaft located within the pillar and guided thereby, a crank at the upper end of the shaft, which is inclined to the axis thereof, a head mounted on the upper end of the pillar, a member mounted on the crank and in which the latter is free to turn while moving in an orbit defined by an inverted cone, a skirt on said member which covers the open end of the head, co-operating means carried by the head and member which prevent the member from rotating with the crank, a yoke carried by the member, bells carried by the arms of the yoke, each of which has an orbital movement, and means for applying power to the lower end of the shaft and below the tub for rotating it.

7. In a washing machine, the combination of a tub, a hollow pillar rising vertically from the bottom of the tub, a shaft located within the pillar and guided thereby, a crank at the upper end of the shaft which is inclined to the axis thereof, an open-ended head which is mounted on the pillar below the crank and has a spherical enlargement which latter has a vertical slot, a member mounted on the crank and in which the latter is free to rotate, a skirt on said member which surrounds said enlargement and is separated therefrom by a relatively small clearance, a pin carried by the skirt which engages the walls of said slot to prevent rotation of the member, a yoke carried by the member, bells carried by the yoke, and means for applying power to the lower end of the shaft and below the tub for rotating it.

In witness whereof I have hereunto set my hand this 13th day of October, 1919.

EARL B. HOFF.
